US0D1098233S

(12) **United States Design Patent** (10) **Patent No.:** **US D1,098,233 S**
(45) **Date of Patent:** **** Oct. 14, 2025**

(54) **CAMERA**

(71) Applicant: **Amazon Technologies, Inc.**, Seattle, WA (US)

(72) Inventors: **Emmanuel Laffon De Mazieres**, Danville, CA (US); **Michael O'Connor**, Charlestown, MA (US); **Jonathan Howard Biddle**, San Francisco, CA (US); **Paul Douglas Gearson**, Salisbury, MA (US); **Thomas Burns**, Patchogue, NY (US)

(73) Assignee: **Amazon Technologies, Inc.**, Seattle, WA (US)

(**) Term: **15 Years**

(21) Appl. No.: **29/907,202**

(22) Filed: **Jan. 4, 2024**

Related U.S. Application Data

(60) Continuation of application No. 29/845,839, filed on Jul. 11, 2022, now Pat. No. Des. 1,016,877, which is a division of application No. 29/726,790, filed on Mar. 5, 2020, now Pat. No. Des. 957,497.

(57) **CLAIM**

The ornamental design for a camera, as shown and described.

DESCRIPTION

FIG. 1 is a top, front, right-side perspective view of a camera showing our new design;

FIG. 2 is a bottom, back, right-side perspective view thereof;

FIG. 3 is a front view thereof;

FIG. 4 is a back view thereof;

FIG. 5 is a left-side view thereof;

(Continued)

FIG. 6 is a right-side view thereof;
 FIG. 7 is a top view thereof; and,
 FIG. 8 is a bottom view thereof.

The dashed broken lines depict portions of the camera that form no part of the claimed design.

1 Claim, 8 Drawing Sheets
